EDUCATIONAL CLOCK TOY

Shirley L. Matricardi, 324 Queisner Ave.,

Lowellville, Ohio

Filed Mar. 15, 1962, Ser. No. 69,280

Term of patent 14 years

(Cl. D25—1)

FIGURE 1 is a front elevational view of an educational clock toy, showing my new design;

FIGURE 2 is a side view thereof; and

FIGURE 3 is a cross sectional elevation taken on line 3—3 of FIGURE 1.

I claim:

The ornamental design for an educational clock toy, as shown.
